SAFETY DEVICE FOR WRINGERS

Walter L. Kauffman, II, Erie, Pa., assignor to
 Lovell Manufacturing Company, Erie, Pa., a
 corporation of Pennsylvania

Application March 17, 1937, Serial No. 131,331

7 Claims. (Cl. 68—253)

It has been common to provide wringers with safety devices. These include devices for releasing the pressure on the rolls and devices for stopping the rolls. The present invention is directed to safety devices and in some of its aspects involves both the means for releasing pressure and for stopping the rolls. One of the objects of the invention is to form these safety devices so that they may be effective with the least possible effort. This is important in that these devices are usually operated under panic conditions and anything that adds to the effort detracts from the safety with which the device operates. The present device is very sensitive in this respect, so much so that it is referred to as the touch control. In the preferred form a common trip mechanism of touch sensitiveness releases both the pressure and stops the rolls.

The invention also involves specific features for improvements in the actuating mechanism for the devices and the relation and position of the trip mechanism. Other features will appear more fully from the specification and claims.

A preferred embodiment of the invention is illustrated in the accompanying drawings as follows:

Fig. 1 shows a front elevation of the wringer.

Fig. 2 an end view of the wringer partly broken away to better show construction.

Fig. 3 an elevation of an end of the wringer partly broken away to better show construction.

Fig. 4 a section on the line 4—4 in Fig. 2.

Fig. 5 a top view of one end of the wringer.

Fig. 6 a plan view of a portion of the reversing gear showing the parts in neutral.

Fig. 7 a similar view with the parts engaged.

Fig. 8 an elevation of the wringer in pressure release position, the water-board being removed to better show construction.

Fig. 9 a section on the line 9—9 in Fig. 4.

Fig. 10 a perspective view of a latch lever.

Fig. 11 an end view, broken away and partly in section, of the driving end of the wringer.

The wringer frame comprises a base 1, side stiles 2, 2, lower and upper rolls 3 and 4 respectively. The lower roll is provided with a shaft 5 which operates in bearings 6, these bearings being placed in the side stiles. The upper roll has a shaft 7 and is provided with bearings 8 which are slidingly mounted in the side stiles. A spring 9 exerts pressure on the upper bearings and consequently pressure on the rolls.

The wringer is provided with a top bar 10, and an adjusting screw 11 is arranged in the top bar

by means of which the spring pressure may be varied. One end of the top bar is hinged at 12 on a gear case 13, the top bar forming the cover of the gear case. The opposite end of the top bar is provided with a resetting mechanism of toggle 5 lever form comprising a lever 14 pivoted at 15 on the top bar and a link 16 pivotally connected to the lever 14 at 17 and to the wringer at 18. This toggle lever operates as a resetting device and also as a release device, the top bar being 10 shown in set position in Fig. 3 and in release position in Fig. 8. By using the top bar as a lever and depressing it, the lever 14 is brought to position so that downward pressure on this lever acting through the link on the toggle principle forces 15 the top bar to its final position. The toggle lever mechanism, it will be noted, in the set position as shown in Figs. 3 and 4, is unstable, that is to say, unless it is retained in the set position it will 20 fly open under the pressure of the spring 9. This is because the pivots 15, 18 and 17 are slightly out of alignment, the link being slightly in the release direction from neutral.

The lower end of the lever 14 is provided with 25 a hook 19 and this is engaged by a hook 21 on a latch 20. The latch 20 is pivotally mounted on a pin 22 in the base. A spring 23 operating on the opposite end of the latch from the hook tends to depress the hook and retain it in engagement and also to automatically crowd the hook into 30 engaging position when the lever is depressed. This hook is subjected to very little pressure by the lever 14 for the reason that the link pivots are very nearly in alignment, as near in alignment as it is practical to go and retain unstable 35 conditions so that a release movement will happen when the lever is released.

The latch 20 is actuated by rock arm 24 which is carried by a rock shaft 25 extending across the base. The rock shaft is pivotally mounted in 40 ears 26 arranged on the base. Rock arms 27 are arranged at each end of the rock shaft and are in position to be actuated by trip members 28, these trip members extending through openings 45 29 in the sides 30 of a water-board 31. The trip members are pivoted on the water-board by pins 32 extending across the sides from wall to wall in the sides. These touch members close the opening 29 and are in convenient position to be 50 operated and do not mar the appearance of the wringer front. It will be understood that this operating mechanism is duplicated at the front and rear of the wringer. A release is effected by touching any one of the four trip members 55

28. The depression of the trip member communicates movement through the rock arms 27, rock shaft 25, and rock arms 24 to the latch 20 so as to release the pressure device.

5 The drive shaft 5 extends into bearings 33 in the gear box frame or case 13. A usual supporting post 34 carries the gear box frame. A drive shaft 35 extends through the post and is fixed with a drive gear 36. The gear 36 meshes with 10 reversing gears 37. The reversing gears 37 are journaled on the shaft 5. The faces of the gears 37 are provided with clutch detents 38 adapted to engage detents 39 on a reversing block 40. The reversing block is slidingly mounted on the 15 shaft 5 between the gears 37 and is locked against rotation on the shaft, spline and groove mechanism 41. The block is provided with an annular groove 42 which receives trunnions 43 extending from the forked end 44 of a lever 45. The lever 20 is pivoted on a rod 46 secured in the gear box. The upper end of the lever is provided with a handle 45a which normally extends above the top bar.

A retaining finger 48 is carried by a trip lever 25 49, the trip lever being pivoted in the case by pins 50. The trip lever has an extending lever arm 51 giving to the lever a bell crank form, and this arm 51 extends above the end of a latch plate 52. The latch plate is pivotally mounted 30 on a pin 53 in the base and is in the path of rock arms 55 on the rock shafts 25.

When the handle 45a is shifted the reversing block 40 is thrown into engagement and locked in this engagement by means of the trip finger 35 48 which, when the lever is swung to driving position, swings into the path of the lever and locks it, the lever 49 swinging forward by gravity. Springs 47 are secured to the lever 45, these 40 springs being secured to the lever and to ears 47a on the case and tending to hold the lever in its neutral position. When the inner end of the trip lever 52 is depressed it lifts the outer end of this lever, thus raising the end 51 of the trip lever 49 and withdrawing the finger 48 which 45 permits the springs 47 to swing the lever 45 to neutral position and thus disengage the clutch. A spring 54 may be provided to depress the outer end of the trip plate 52. Thus there is a mere withdrawal of the latch formed by the finger 50 48 to effect a disengagement of the clutch. It will be understood that the rock arm 55 being on the rock shaft 25 is tripped each time one of the four trip members 28 are actuated.

The levers and trip members are related so 55 that with an initial downward movement of a trip member, the rock arm 55 engages the trip plate 52 and withdraws the finger 48 to stop the rolls and a further depressing of the trip member 28 operates the latch and effects the release of pressure 60 sure, these positions being shown in Fig. 11. It will be understood, however, that either sequence may be arranged, or the releases may be made simultaneously by merely adjusting the inter-connecting parts.

65 While I have shown the top bar with its hinge offset from the stile and forming a covering for the gear case, I do not claim these features in this application. These features are shown and are the subject of claims in my applications 70 131,335 and 131,338, filed March 17, 1937, entitled "Wringer mechanism" and "Wringers," respectively.

What I claim as new is:

1. In a wringer, the combination of a frame; 75 rolls mounted in the frame; means exerting

pressure on the rolls; a gear mechanism driving a roll; an unstable release device for the pressure means; a retaining device retaining the release device in set position; an unstable setting device for the gear mechanism tending to release the 5 mechanism when the device is released; a retaining device retaining the setting device in set position; trip mechanisms at the front and rear of the wringer each effecting the release of both retaining devices, comprising a rock shaft extending along and lengthwise of the frame and operating connections at the ends of the wringer between the shaft and the retaining devices; and trip members actuating the rock shaft, said trip members being exposed to manual pressure alone 10 and through such pressure effecting a release.

2. In a wringer, the combination of a frame; rolls mounted in the frame; means exerting pressure on the rolls; a gear mechanism driving a roll; an unstable release device for the pressure 20 means; a retaining device retaining the release device in set position; an unstable setting device for the gear mechanism tending to release the mechanism when the device is released; a retaining device retaining the setting device in set position; trip mechanisms at the front and rear of the wringer each effecting the release of both retaining devices, comprising a rock shaft extending along and lengthwise of the frame and operating 25 connections at the ends of the wringer between the shaft and the retaining devices; and trip members at different points on the rock shaft, said trip members being exposed to manual pressure alone, and through such pressure effecting a release. 35

3. In a wringer, the combination of a frame; rolls mounted in the frame; means exerting pressure on the rolls; a gear mechanism driving a roll; an unstable release device for the pressure means; a retaining device retaining the release 40 device in set position; an unstable setting device for the gear mechanism tending to release the mechanism when the device is released; a retaining device retaining the setting device in set position; trip mechanisms at the front and rear 45 of the wringer each effecting the release of both retaining devices, comprising a rock shaft extending along and lengthwise of the frame and operating connections at the ends of the wringer between the shaft and the retaining devices; and trip members operating on the rock shaft at the ends of the wringer, said trip members being exposed to manual pressure alone, and through such pressure effecting a release.

4. In a wringer, the combination of a frame; 55 rolls mounted in the frame; means exerting pressure on the rolls; a gear mechanism driving a roll; an unstable release device for the pressure means; a retaining device retaining the release device in set position; an unstable setting device 60 for the gear mechanism tending to release the mechanism when the device is released; a retaining device retaining the setting device in set position; trip mechanisms at the front and rear of the wringer each effecting the release of both 65 retaining devices, comprising a rock shaft extending along and lengthwise of the frame and operating connections between the shaft and the retaining devices; and a water-board extending along the front of the wringer and below the 70 bite of the rolls, said water board guarding the rock shaft from the action of the clothes.

5. In a wringer, the combination of a frame; rolls mounted in the frame; means exerting pressure on the rolls; a gear mechanism driving a 75

roll; an unstable release device for the pressure means; a retaining device retaining the release device in set position; an unstable setting device for the gear mechanism tending to release the mechanism when the device is released; a retaining device retaining the setting device in set position; trip mechanisms at the front and rear of the wringer each effecting the release of both retaining devices, comprising a rock shaft extending along and lengthwise of the wringer and operating connections between the shaft and the retaining devices; a water-board along the front of the wringer and below the bite of the rolls guarding the rock shaft from the action of the clothes; and a trip member at an end of the wringer for actuating the rock shaft.

6. In a wringer, the combination of a frame; rolls mounted in the frame; means exerting pressure on the rolls; a gear mechanism driving a roll; a safety device for the wringer; a rock shaft extending along and lengthwise of the wringer

and having an actuating connection at the end of the wringer controlling the safety device; a water-board extending along the front of the wringer and below the bite of the rolls guarding the rock shaft from the action of the clothes; and a trip member at an end of the wringer for actuating the rock shaft.

7. In a wringer, the combination of a frame; rolls mounted in the frame; means exerting pressure on the rolls; a gear mechanism driving a roll; a safety device for the wringer; a rock shaft extending along and lengthwise of the wringer and having an actuating connection at the end of the wringer controlling the safety device; a water-board extending along the front of the wringer and below the bite of the rolls guarding the rock shaft; and a trip member at an end of the wringer for actuating the rock shaft, the water-board having an orifice through which the trip member extends.

WALTER L. KAUFFMAN, II.
